CLAIM

The ornamental design for a steering wheel as shown and described.

DESCRIPTION

FIG. 1 is front perspective view of a steering wheel showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in FIGS. 1-8 represent portions of the steering wheel that form no part of the claimed design. The dot-dash broken lines in FIGS. 1-8 represent unclaimed boundary lines and form no part of the claimed design.

1 Claim, 7 Drawing Sheets
